UNITED STATES PATENT OFFICE.

VAUGHN H. ROSS, OF VANCOUVER, BRITISH COLUMBIA, CANADA.

WIRE-TYING MACHINE.

Application filed November 23, 1926. Serial No. 150,345.

This invention relates to wire tying machines such as are used in connection with the securing of wire-bound packages. It has specific reference to a machine of the character described hereinafter, the invention residing in the addition of a crank spindle which affords a quick speed when fine gauge wires are used, thus greatly increasing the efficiency of the machine.

10 The invention is better and fully described by reference to the drawings herewith forming part of this application in which:

Fig. 1 is a side elevation of the machine, and

15 Fig. 2, an end view.

The characteristics of the machine are more easily understood by tracing its operation and meanwhile noting the function of the several parts.

20 The wire used for a given line of work is cut to length, one end being inserted in the wire grip 3 and there secured by the clip 4 which is raised as the wire is threaded along and into the groove 5 at which point 25 it is engaged by a slot in the pinion 6, which pinion in being revolved by the gear wheel 7 ultimately twists the ends of the wires together. After being threaded into the groove 5 the wire is passed under the 30 wire cutter 8, thence passing round the package and again re-inserted through 3, 4, 5 but through the wire cutter 8, the end being finally slipped into any of the angular 35 slots 9 of the ratchet wheel 10.

35 The wire being thus threaded in position as a loop is tightened to the required tension by movement of the hand lever 11, after which a few turns of the crank 12 completes

the operation of twisting the wires together and cutting off the end. 40

It will be noted that the operation thus described has been accomplished by the hand crank 12 revolving the pinion 13, which pinion meshes with the gear wheel 7, thus giving a slower and more powerful motion 45 such as would be required by the stouter class of wires but is unnecessarily slow when fine wires are being dealt with.

It is this latter condition that my invention is designed to remedy by providing the 50 spindle 14 as a secondary crank-shaft instead of using a stud upon which to revolve the gear wheel 7 as hitherto employed, so that with a view to raise the speed I eliminate the use of the pinion 13 and place the 55 hand-crank 12 directly upon the gear wheel spindle 14 but revolving the same in the opposite direction to that required by the spindle 15. By this arrangement a single 60 turn of the hand-crank completes the operation.

Having now particularly described my invention, what I claim and desire to be protected in by Letters Patent is:—

In a wire tying machine of the type described the combination comprising, a 65 spindle, a gear wheel secured to said spindle, a hand crank removably secured to said spindle, two pinions meshing with the said gear wheel, one of said pinions being slotted 70 to receive and twist the tying wire used in said machine, a spindle secured to the other said pinion and adapted to also receive said removable hand crank.

In testimony whereof I affix my signature.

VAUGHN H. ROSS.
